UNITED STATES PATENT OFFICE.

GEORGES GUSTAVE URBAIN MARIE MAIRESSE, OF PARIS, FRANCE.

PROCESS FOR FINISHING TEXTILE MATERIALS.

Application filed March 19, 1924. Serial No. 700,325.

To all whom it may concern:

Be it known that I, GEORGES GUSTAVE URBAIN MARIE MAIRESSE, a citizen of the French Republic, residing at Paris, France, have invented new and useful Improvements in Processes for Finishing Textile Materials, of which the following is a specification.

This invention relates to improvements in processes for finishing, that is to say stamping, embossing and goffering textiles, leathers and other similar articles.

This process consists essentially in this that between the textile, leather or other article to be finished, and the embossing or goffering roller which is raised to a sufficient temperature (about 50° to 60° C.), there is interposed a carrier-sheet of paper or other appropriate support coated previously with a thin layer of white paraffin wax, stearine or other suitable fatty body placed against the textile, leather or other article to be embossed (stamped) or goffered. At the moment of such embossing or goffering and under the action of the heat from the embossing or goffering roller, the paraffin or other fatty body so interposed, melts at the places where it is subjected to the pressure of the parts in relief on the roller, and soaks into the textile, fabric, leather or other article, at those places only.

By reason of this improvement, the paraffin or other fatty body absorbed at the embossed or (stamped) or goffered places, avoids the waxed and brilliant appearance generally produced by these operations and affords on the contrary at these parts a desirable dull or matt effect; further, it imparts to the fabrics so prepared, a very noticeable appearance or finish; lastly, when the embossing or goffering acts on a sufficiently thick textile, the paraffin or other fatty body incorporated, causes in some degree the threads of this textile to adhere, or to be flattened, one against another and, maintaining them in their crushed position, increases the solidity and the longevity of the embossing or goffering.

The textiles, leathers or other articles are, moreover, rendered waterproof at the places thus treated, so that straightening or relaxing of the threads or fibres due to damp is avoided.

The interposition of the paper or other support coated with paraffin or other appropriate fatty body between the textile,

leather or other article to be embossed (stamped) or goffered and the embossing or stamping roller, can be effected in any desired manner.

The annexed drawing shows by way of example a diagram of a mechanical arrangement which permits the utilization of this process.

In this drawing, *a* represents the engraved, and heated roller and *b* the smooth-surfaced roller forming the pressure cylinder. The fabric *c* to be pressed, wound upon the roller *d*, is, after the pressing operation, wound around the roller *e*. The carrier sheet, made for example of paraffined paper *f* wound on the roller *g* and guided by the rollers *h* and *h'* is, after having been used, wound upon the roller *i*.

The textiles to which this invention relates may be of silk, cotton, wool or the like, and smooth or of a plush-like nature.

The roller *a* engraved in relief shows the design or pattern which is to be reproduced upon the textile by the flattening of the fibres of the textile, velours, for example. A leather or fabric can be embossed with a raised pattern, the ground being stamped or sunk. A cotton fabric can be stamped or goffered with an embossed pattern.

By reason of the deposition of the fatty body in the parts embossed or stamped, the textile or other material receives a finish which causes the fibres of the material to remain flattened down.

When the invention is to be applied to existing embossing machines, the roller for the paraffined paper can be carried on two arms adapted to be fixed to the machine.

The paraffined paper having been passed between the engraving roller and the textile, need not necessarily be wound upon a receiving roller.

Having thus described my invention what I claim is:—

1. Process of finishing textiles, leather and other similar material which consists in passing the material between rollers, said rollers comprising an engraved roller and a smooth-surfaced pressure roller, heating said engraved roller, and interposing between the material to be finished and the engraved roller, a carrier-sheet coated with a thin layer of a fatty body, so that said fatty layer is pressed against the material as it passes between the rollers.
2. Process of finishing textiles, leather and

other similar material which comprises passing the material between rollers, one of said rollers being heated and comprising an engraved surface and the other roller having a smooth surface, and simultaneously interposing between said rollers a carrier-sheet of flexible material coated with a fatty body, in such a way that the fatty body makes contact with the material to be finished.

3. Process of finishing textiles, leather and other similar material, which consists in passing the material between a heated, engraved roller and a smooth-surfaced pressure roller, interposing between the material and the engraved roller a flexible carrier-sheet previously coated with white paraffin wax and placing the coated side of said carrier-sheet against the material to be finished, whilst said material and coated sheet are passing between the rollers.

4. Process of finishing textiles, leather and other similar material, which consists in passing the material between a heated roller, engraved in relief, and a smooth-surfaced pressure roller, interposing between the material and the engraved roller, a carrier-sheet having on one side a layer of a fatty body, and transferring to the material by the heat and pressure from the engraved roller, the fatty body from the carrier-sheet in such a way as to retain flattened down those fibres of the material which have been stamped

down by the parts in relief upon the engraved roller.

5. Process of finishing textiles, leather and other similar materials, which consists in passing the material between an engraved roller and a smooth-surfaced pressure roller, interposing between said material and the engraved roller a carrier-sheet coated on one side with a thin layer of a fatty body, and depositing the fatty body upon the material at those places which are subjected to the pressure of the parts in relief upon the engraved roller, by means of heat supplied from the engraved roller.

6. Process of finishing textiles, leather and similar materials which consists in passing the material between a heated, engraved roller and a smooth-surfaced pressure roller, interposing between the material and the engraved surface of the heated roller a carrier-sheet coated on one side with a fatty body, stamping the material by the raised portions of the engraved roller to form sunk grounds upon the material to be finished, and applying to said sunk grounds the fatty body melted by the heat of the engraved roller and deposited upon the material by the parts in relief of the engraved surface of the heated roller.

In testimony whereof I have signed my name to this specification.

GEORGES GUSTAVE URBAIN MARIE MAIRESSE.
